TUFTING MACHINE

Samuel P. Parker, La Grange, Ga., assignor, by
mesne assignments, to Callaway Mills Company,
La Grange, Ga., a corporation of Georgia

Application June 22, 1946, Serial No. 678,603

18 Claims. (Cl. 112—79)

1

This invention relates to machines for inserting tufts of yarn or thread in a backing material and is concerned more particularly with a novel tufting machine, which can be operated with facility for the insertion of tufts to produce either simple or intricate designs. The new machine functions in such manner that the operator may insert tufts in the backing material along curved lines or in any lateral direction at will and without stopping the machine or turning the material, so that the machine may be operated on such work at a higher output rate than prior tufting machines. The new machine is simple in construction and may be easily maintained in good working order.

Tufting machines, as heretofore constructed, have commonly included a needle for passing the loops of yarn through the backing fabric and a looper for engaging each loop so inserted by the needle and holding it as the needle is retracted. The loops are ultimately severed to produce tufts and, in some machines, the looper is formed with a cutting edge and the loops accumulate on the looper, until the addition of another loop causes the first preceding uncut loop to be moved over the cutting edge and severed. In other machines, cutting means independent of the looper are employed and the cutting devices are actuated at the proper times to sever the yarns and produce the tufts. In the prior machines, it is common to hold the material being tufted against a throat plate having an opening, through which the needle passes, and to feed the backing material over the plate by a mechanically operated feed dog. As the feeding device advances the material in one direction only with reference to the needle, a change in the direction of the row of tufts to be inserted can only be effected by stopping the machine, releasing the presser foot, turning the material as required, lowering the presser foot, and starting the machine. Such machines can, accordingly, be used only with difficulty in the production of articles tufted in intricate designs.

The present invention is directed to the provision of a tufting machine which overcomes the difficulties involved in the operation of prior machines and enables the operator to insert tufts in the backing material in any direction, as desired, and without stopping the machine or turning the material. In the new machine, the backing material is held in place only for a part of each reciprocation of the needle and is then released, so that the operator may shift it as he wishes. Although each loop inserted is severed before another loop is passed through the mate-

2

rial, each loop is retained in place by the looper while the needle is being retracted, so that the loop is not pulled free of the backing.

For a better understanding of the invention, reference may be had to the accompanying drawings, in which:

Fig. 1 is a vertical sectional view through a tufting machine constructed in accordance with the invention;

Fig. 2 is a view of the machine in end elevation;

Fig. 3 is a fragmentary sectional view on the line 3—3 of Fig. 2, with some parts broken away and others shown in plan;

Fig. 4 is a fragmentary sectional view on the line 3—3 of Fig. 2, with parts shown in plan;

Figs. 5, 6 and 7 are sectional views on the line 5—5 of Fig. 3, showing the parts in different positions; and

Figs. 8 and 9 are fragmentary vertical sectional views showing the operation of severing a loop.

The tufting machine illustrated in the drawings includes the usual bed 10, from one end of which rises a standard 11 provided with an arm 12 which overhangs the bed and terminates in a head 13 at its free end. A horizontal drive shaft 14 extends through the arm 12 and projects into the head at one end and out of the arm at the other. The shaft is mounted for rotation in suitable bearings and carries a drive pulley 15 and a hand wheel 16 on the end exposed beyond the arm. A cam member 17 for operating a tension device, which forms no part of the invention, is mounted on the end of the shaft 14 within head 13, and a cam plate 18 is mounted on the shaft 14 against the outer face of the cam member. An eccentric pin 19 extends outwardly from the face of cam plate 18 and is connected by a link 20 to a pin 21 attached by means of a clamp 22 to a needle bar 23 mounted for vertical reciprocation in aligned openings in head 13. At the lower end of the bar, a needle 24 is removably secured thereto.

The end 10a of the bed beneath the head 13 is of tubular form and a curved throat plate 25 is secured on top of the tubular part of the bed and projects beyond the end of the bed. The plate has an opening 25a aligned with the needle, and, when the needle bar and needle are reciprocated, the needle passes through the opening. A rod 26, mounted in aligned openings in head 13 and extending parallel to the needle bar, carries a presser foot 27 at its lower end, the foot having an opening 27a through which the needle passes in its reciprocation. A clamp 28 is mounted on rod 26 within the head 13 and springs 29 and 30

encircles the rod 26 above and below clamp 28, each spring bearing at one end against a wall of the head and at the other end against clamp 28. Spring 29 is stronger than spring 30 and normally acts to hold the presser foot against the upper surface of the throat plate, while spring 30 acts as a shock absorber. Rod 26 projects upwardly through the top wall of head 13 and, at its upper end, the rod carries an arm 31 which extends into a slot in a rod 32 which projects through an opening in the top wall of the head, and lies with its lower end above the edge of the cam disk 18. As shaft 14 rotates, it reciprocates the needle bar and needle vertically, and the cam disk 18 acts through pin 32 to raise the rod 26 and presser foot 27 once per revolution of the shaft. The mechanism is so timed that the presser foot lies in its down position until after the needle has been raised free of the foot, after which the rod 26 and the foot are raised. The rod and foot are then permitted to move downwardly just before the point of the needle enters the opening 27a in the presser foot.

The clamp 28 on the presser foot rod 26 is provided with an arm 33, which may be engaged by a cam surface on the tail 34 of a handle 35 pivotally mounted on a portion of the head. When the handle 35 is swung clockwise (Fig. 2), the tail bears against arm 33 and raises rod 26 and presser foot 27. When the handle is turned far enough, the flat end of tail 34 engages arm 33, so that the presser foot is held in raised position, until the handle is turned to release it.

A rock shaft 36 is mounted for oscillation in downward projections 37, 38 from the bed 10, and at one end, the rock shaft carries a collar 39, from which extends an arm 40 provided with a pin 41, on which is mounted a roller 42. The roller lies in a channel 43 on an arm 44 which is loosely mounted on a rod 45 supported between extension 37 and another downward extension 46 from the bottom of the bed. The arm 44 is provided with a pin 47, to which is attached one end of a connecting rod 48, the other end of the rod being mounted on a crank pin 49 connecting crank arms 50, 50 on the drive shaft 14. As the drive shaft rotates, it causes arm 44 to oscillate and this in turn causes oscillation of the rock shaft 36.

A flat ring 51 is mounted in the tubular end of the bed 10, and a disk 52 is mounted loosely on the rock shaft 36 within ring 51, and held in place by a nut 53 on the end of the shaft. The disk is formed with a slot 54 extending inwardly from its edge, and a looper is mounted on the disk at one side of the slot. The looper comprises a plate 55 provided with a hook 56 at its outer end, the plate being mounted in a channel in the face of disk 52. Plate 55 is formed with a slot 55a through which extends a screw 57 threaded into disk 52, the slot and screw mounting permitting the position of the plate with reference to the disk to be varied as desired. In the operation of the machine, disk 52 is oscillated and the plane of oscillation of the looper is substantially tangent to the path of reciprocation of the needle, so that hook 56 may enter a loop of yarn carried by the needle.

The ring 51 is formed in its outer face at its top with a radial channel 58 through which the needle may pass, and a cutting block 59 is mounted against the outer face of the ring at one side of the channel. The hook 56 of the looper is provided with a cutting edge 60, which is adapt-

ed to cooperate with one edge of the cutting block to effect a shear cut.

A pair of pins 61, 62 extend outward from the rear face of disk 52 and lie in diametrical relation at opposite sides of shaft 36. These pins are engageable by enlarged heads on rods 63, 64 which are mounted in openings in guides 65 in a block 66 attached to the lower end of extension 38 from the bed. The lower end of each rod 63, 64 is shouldered and the reduced end portion enters one end of a spring 67 which lies within a bore in block 66 and is seated at its lower end against the bottom of the bore. Springs 67 are of equal force, and act through rods 63, 64 on pins 61, 62 to maintain disk 52 with the pins in horizontal alignment. When the disk 52 is in this angular position, the looper extends vertically, as shown in Fig. 6, with the side of the plate 55 from which hook 56 extends, substantially in alignment with the axis of the needle.

A central hub 68 extends rearwardly from disk 52 to encircle rock shaft 36 and the hub is formed with a single radial projection 69. A collar 70 is mounted fast on shaft 36 adjacent the rear face of the hub and the collar has a recess in one face into which the projection 69 extends. The recess is defined by spaced radial shoulders 71, 72.

The rock shaft 36 is encircled by spring 73 which is compressed between a collar 74 fast on the shaft and one face of the extension 37 from the bed. A pin 75 mounted in extension 37 projects beyond one face thereof and, as shaft 36 rocks, the end of the pin is engaged by a roller 76 loosely mounted on a pin 77 mounted in collar 39. As the roller rides over the end of the pin, shaft 36 is caused to move to the right (Fig. 1) against the action of spring 73.

In the operation of the machine, the presser foot is first raised above the throat plate by handle 35 and the hand wheel 16 is turned to move the needle to its upper position. The material to be tufted is then placed on the throat plate with the point where the first stitch is to be made over the opening in the throat plate, after which handle 35 is turned to release the presser foot and the machine is started. As shaft 14 is rotated, the needle is vertically reciprocated, and, as the needle approaches the material on the throat plate, the cam disk 18 has moved to a position such that spring 29 is free to move rod 26 downwardly to cause the presser foot 27 to clamp the material against the throat plate. While the needle is passing a loop of yarn through the material on the throat plate, the disk 52 is being held in the position shown in Fig. 5 by engagement of shoulder 71 on collar 70 on the rock shaft. In this position of disk 52, pin 61 lies free of the enlarged head on the spring-pressed rod 63, while pin 62 has been moved to depress rod 64 against the action of its spring 67. When the needle reaches its lowermost position, the rock shaft begins to move counterclockwise (Fig. 5) and, as shoulder 71 tends to move away from projection 69, the projection is kept in contact with the shoulder by the action of spring-pressed rod 64 on pin 62. Disk 52 is, accordingly, moved to cause the hook 56 to enter the loop of yarn carried by the needle, and, as the needle rises, the loop is held by the hook. When the disk 52 reaches the position in which its pins 61, 62 are horizontally aligned, collar 70 continues its movement with rock shaft 36 and shoulder 71 moves away from the face of projection 69, with which it was previously in contact. The disk 52 then remains at rest, until shoulder 72 on collar 70

engages projection 69 and causes the projection and disk 52 to move with it.

During the interval, in which disk 52 is at rest, the needle has moved upwardly and is clear of the material, and, when the needle reaches its uppermost position, the movement of disk 52 by engagement of shoulder 72 on collar 70 with projection 69 on the disk is resumed. The loop of yarn held by the hook 56 is then carried along by the hook and the loop slides along the hook to overlie the cutting edge 60 on the hook. As the cutting edge approaches the edge of the cutting block 59, the roller 76 on pin 77 carried by collar 39 on the rock shaft rides over the end of the pin 75 and this causes the rock shaft to be moved endwise, so that the cutting edge 60 on the hook cooperates with the edge of the cutting block to sever the yarn with a shear cut.

When the needle has been moved free of the material and is approaching its uppermost position, the presser foot 27 is raised to release the material. The operator then shifts the material over the throat plate to bring the next point on the material, where a tuft is to be inserted, into alignment with the needle. Meanwhile, upon completion of the severance of the loop, the rock shaft starts to return to its original position and, during that movement, projection 69 is kept in contact with the shoulder 72 on collar 70 until plate 52 reaches the position in which pins 61, 62 are horizontally aligned. The plate then remains at rest, until shoulder 71 on collar 70 engages projection 69 and causes a further movement of plate 52 to the position shown in Fig. 5. During the return movement of the plate, the needle is again descending, and, as it approaches the material, the presser foot is lowered to clamp the material against the throat plate to permit the insertion of another tuft.

It will be seen that the new tufting machine is so constructed that, during a part of the reciprocation of the needle and while the needle is free of the material, the presser foot is raised from the material so that the operator can shift the material in any direction. Accordingly, he can insert a succession of tufts along a curved line or in any lateral direction without turning of the material. Each loop inserted is held by the hook of the looper, as the needle rises, to prevent the inserted loop from being withdrawn, and, as the needle approaches its topmost position, the loop is severed and the looper moves back ready to function when the next loop has been inserted. The path of oscillation of the plate 55 lies substantially tangent to the path of travel of the needle at one point, and the disk 52 is biased to hold plate 55 in its tangential relation to the path of travel of the needle. The shoulders 71, 72 on collar 70 act to move disk 52 positively from that central position only toward the ends of its path of oscillation and the return movement of disk 52 to its central position is produced by the biasing means acting upon it. The projection 69 and collar 70 provide a lost-motion connection between the rock shaft 36 and plate 52 and, by virtue of this connection and the biasing means acting on the plate, the looper oscillates with a period of rest in the middle of its movement in both directions.

I claim:

1. In a tufting machine having a throat plate against which the material to be tufted rests and means, including a reciprocating needle passing through an opening in the plate, for carrying loops of yarn through the material, the combina-

tion of means operating alternately to hold the material against movement relative to the plate and to release the material, a looper having a cutting edge, a member with which the cutting edge cooperates to effect a shear cut, and means for operating the looper to cause it to enter successive loops of yarn carried through the material by the needle, to hold each loop until the needle has moved clear of the material, and to cooperate with the member to sever the loop.

2. In a tufting machine having a throat plate against which the material to be tufted rests and means, including a reciprocating needle passing through an opening in the plate, for carrying loops of yarn through the material, the combination of means operating alternately to hold the material against movement relative to the plate and to release the material, a looper having a cutting edge and mounted to oscillate about an axis at an angle to the path of travel of the needle, a member with which the cutting edge cooperates, and means for oscillating the looper to cause it to enter successive loops of yarn carried through the material by the needle and to cooperate with the member to sever the loops, said means causing the looper to come to rest at the middle of its movement in one direction to hold the loop until the needle has moved clear of the material.

3. In a tufting machine having a throat plate against which the material to be tufted rests and means, including a reciprocating needle passing through an opening in the plate, for carrying loops of yarn through the material, the combination of means operating alternately to hold the material against movement relative to the plate and to release the material, a looper having a cutting edge and mounted to oscillate about an axis at an angle to the path of travel of the needle, a member with which the cutting edge cooperates, and means for oscillating the looper to cause it to enter successive loops of yarn carried through the material by the needle and to cooperate with the member to sever the loops, said means causing the looper to come to rest after entering each loop to hold the loop until the needle has moved clear of the material, and means for causing a relative shifting movement of the looper and member to bring the cutting edge and member into cooperative relation.

4. In a tufting machine having a throat plate against which the material to be tufted rests and means, including a reciprocating needle passing through an opening in the plate, for carrying loops of yarn through the material, the combination of means operating alternately to hold the material against movement relative to the plate and to release the material, a looper having a cutting edge and mounted to oscillate about an axis at an angle to the path of travel of the needle, means biasing the looper toward a position at the middle of its path of oscillation, a member with which the cutting edge cooperates, and means for positively moving the looper from said position toward opposite ends only of said path, said biasing and moving means being constructed to cause the looper to advance toward the needle and enter the loop, to remain at rest until the needle has moved clear of the material, and to advance to cooperating relation with the member.

5. In a tufting machine having a throat plate against which the material to be tufted rests and means, including a reciprocating needle passing through an opening in the plate, for carrying loops of yarn through the material, the combina-

tion of a looper having a cutting edge and mounted to oscillate about an axis at an angle to the path of travel of the needle, and means for causing the looper to oscillate with a period of rest in the middle of its movement in at least one direction.

6. In a tufting machine having a throat plate against which the material to be tufted rests and means, including a reciprocating needle passing through an opening in the plate, for carrying loops of yarn through the material, the combination of a looper mounted to oscillate about an axis at an angle to the path of travel of the needle, and means for causing the looper to oscillate with a period of rest in the middle of its movement in at least one direction.

7. In a tufting machine having a throat plate against which the material to be tufted rests and means, including a reciprocating needle passing through an opening in the plate, for carrying loops of yarn through the material, the combination of a looper mounted for movement back and forth along a curved path which lies substantially tangent at one point to the path of travel of the needle, and means for moving the looper with a period of rest at said point.

8. In a tufting machine having a throat plate against which the material to be tufted rests and means, including a reciprocating needle passing through an opening in the plate, for carrying loops of yarn through the material, the combination of a looper mounted for movement back and forth along a path which lies substantially tangent at one point to the path of travel of the needle, spring means for biasing the looper toward said point, and means for positively moving the looper only from said point toward opposite ends of its path, said means being constructed to permit the looper to have a period of rest at said point.

9. In a tufting machine having a throat plate against which the material to be tufted rests and means, including a reciprocating needle passing through an opening in the plate, for carrying loops of yarn through the material, the combination of a looper mounted for oscillation about an axis along a path lying substantially tangent at one point to the path of travel of the needle, spring means acting on the looper on opposite sides of its axis of oscillation and biasing the looper toward said point, and means operable to move the looper positively only away from said point toward the ends of its path, said moving means disengaging the looper to permit it to have a period of rest at said point.

10. In a tufting machine having a throat plate against which the material to be tufted rests and means, including a reciprocating needle passing through an opening in the plate, for carrying loops of yarn through the material, the combination of a rock shaft, a looper mounted for oscillation about the axis of the shaft along a path which is substantially tangent at one point to the path of travel of the needle, spring means biasing the looper toward said point, and means on the shaft operable on the looper and positively moving it only outwardly from said point toward the ends of its path.

11. In a tufting machine having a throat plate against which the material to be tufted rests and means, including a reciprocating needle passing through an opening in the plate, for carrying loops of yarn through the material, the combination of a rock shaft, a looper mounted for oscillation about the axis of the shaft along a path

which is substantially tangent at one point to the path of travel of the needle, the looper having a cutting edge, spring means biasing the looper toward said point, means on the shaft operable on the looper and positively moving it only outwardly from said point toward the ends of its path, a member with which the cutting edge cooperates to effect a cut, and means for causing a relative shifting movement of the looper and member, when the looper is moving toward one end of its path, to cause the cutting edge and member to cooperate to effect a cut.

12. In a tufting machine having a throat plate against which the material to be tufted rests and means, including a reciprocating needle passing through an opening in the plate, for carrying loops of yarn through the material, the combination of a rock shaft, a looper mounted for free rotation on the shaft but restrained against movement along the shaft, the plane of rotation of the looper lying substantially tangent to the path of travel of the needle, spring means acting on the looper at diametrical points and biasing it toward the path of travel of the needle, and an element mounted on the shaft for rotation therewith and having angularly spaced working surfaces alternately operable on the looper, as the shaft rocks, said element causing positive movement of the looper only away from the path of travel of the needle.

13. In a tufting machine having a throat plate against which the material to be tufted rests and means, including a reciprocating needle passing through an opening in the plate, for carrying loops of yarn through the material, the combination of a rock shaft, a looper mounted for free rotation on the shaft but restrained against movement along the shaft, the looper having a cutting edge and the plane of rotation of the looper lying substantially tangent to the path of travel of the needle, spring means acting on the looper and biasing it toward the path of travel of the needle, an element mounted on the shaft and having angularly spaced working surfaces alternately operable on the looper, as the shaft rocks, said element causing the looper to move only away from the path of travel of the needle, a member adapted to cooperate with the cutting edge to cause the edge to effect a cut, and means for moving the shaft endwise to bring the cutting edge and member into cooperative relation.

14. In a tufting machine, the combination of a drive shaft, a needle bar reciprocated by the drive shaft, a needle mounted on the needle bar, a throat plate against which the material to be tufted rests, the throat plate having an opening through which the needle passes, a rock shaft connected to the drive shaft to be rocked thereby, a looper movable in a plane substantially tangent at one point to the path of travel of the needle, means biasing the looper toward said point, and a connection between the looper and the rock shaft through which the rock shaft moves the looper only away from said point in opposite directions in alternation with a period of rest at said point.

15. In a tufting machine, the combination of a drive shaft, a needle bar reciprocated by the drive shaft, a needle mounted on the needle bar, a throat plate against which the material to be tufted rests, the throat plate having an opening through which the needle passes, a rock shaft connected to the drive shaft to be rocked thereby, a looper movable in a plane substan-

tially tangent at one point to the path of travel of the needle, means biasing the looper toward said point, a connection between the looper and the rock shaft through which the rock shaft moves the looper only away from said point in opposite directions in alternation with a period of rest at said point, means for holding the material against the throat plate, and means operated by the drive shaft for causing the holding means to be alternately effective and ineffective.

16. In a tufting machine, the combination of a needle bar, a needle mounted on the needle bar, a throat plate against which the material to be tufted rests, the throat plate having an opening through which the needle passes, a drive shaft for reciprocating the needle bar, a rock shaft, a disk loosely mounted on the rock shaft, a looper mounted on the disk and having a cutting edge, the looper being movable with the disk in a plane substantially tangent to the path of reciprocation of the needle with the needle bar, spring means acting on the disk at diametrical points and tending to hold the disk with the looper in a position extending along the path of travel of the needle, and a lost-motion connection between the rock shaft and the disk, through which the rock shaft positively moves the disk and looper only away from said position with a period of rest at said position.

17. In a tufting machine, the combination of a needle bar, a needle mounted on the needle bar, a throat plate against which the material to be tufted rests, the throat plate having an opening through which the needle passes, a drive shaft for reciprocating the needle bar, a rock shaft, a disk loosely mounted on the rock shaft, a looper mounted on the disk and having a cutting edge, the looper being movable with the disk in a plane substantially tangent to the path of reciprocation of the needle with the needle bar, spring means acting on the disk at diametrical points and tending to hold the disk with the looper in a position extending along the path of

travel of the needle, a member adjacent the path of travel of the looper with which said cutting edge cooperates to effect a cut, and a lost-motion connection between the rock shaft and the disk, through which the rock shaft positively moves the disk and looper only away from said position with a period of rest at said position.

18. In a tufting machine, the combination of a needle bar, a needle mounted on the needle bar, a throat plate against which the material to be tufted rests, the throat plate having an opening through which the needle passes, a drive shaft for reciprocating the needle bar, a rock shaft, a disk loosely mounted on the rock shaft, a looper mounted on the disk and having a cutting edge, the looper being movable with the disk in a plane substantially tangent to the path of reciprocation of the needle with the needle bar, spring means acting on the disk at diametrical points and tending to hold the disk with the looper in a position extending along the path of travel of the needle, a member adjacent the path of travel of the looper cooperable with said cutting edge, a lost-motion connection between the rock shaft and the disk through which the rock shaft positively moves the disk and looper only away from said position with a period of rest at said position, and means for shifting the rock shaft endwise as the looper approaches said member to cause said cutting edge member to effect a shear cut.
